UNITED STATES PATENT OFFICE.

ISAAC C. H. GILMORE AND HENRY B. STAFFORD, OF OSKALOOSA, IOWA.

SAD-IRON.

SPECIFICATION forming part of Letters Patent No. 381,006, dated April 10, 1888.

Application filed June 3, 1887. Serial No. 240,170. (No model.)

To all whom it may concern:

Be it known that we, ISAAC C. H. GILMORE and HENRY B. STAFFORD, citizens of the United States, residing at Oskaloosa, in the county of 5 Mahaska and State of Iowa, have invented a new and useful Improvement in Sad-Irons, of which the following is a specification.

Our invention relates to an improvement in sad-irons; and it consists in the peculiar construction and combination of devices, that will be more fully set forth hereinafter, and, particularly pointed out in the claims.

This invention is an improvement upon the sad-iron for which Letters Patent of the United 15 States No. 346,814 were granted to B. F. Hostetter and I. C. H. Gilmore August 3, 1886.

In the drawings, Figure 1 is a vertical longitudinal sectional view on the line xx of Fig. 2 of an iron embodying our improvements. 20 Fig. 2 is a rear elevation of the same. Fig. 3 is a top plan view of the same with the top of the iron removed.

A represents the body or shell of the iron, which is made of cast metal and has the side 25 walls, B, and the bottom C. The rear end of the shell or body is open. On the lower side of the iron, at the rear end thereof, is formed an upwardly-projecting transverse flange, D, and at the sides of the iron, at the rear end 30 thereof, are formed inwardly-extending flanges

E, which align with the flange D. At a suitable distance from the inner side of the vertical flanges E are vertical offsets or posts F, which are also cast integrally with the shell or 35 body, and wedge-shaped grooves G are formed between the opposing sides of the flanges E and the posts F, the said grooves being wider at their upper ends than at their lower ends. In the opposing sides of the posts or offsets F, 40 at the front corners thereof, are formed vertical recesses H. In the front end of the shell or body is formed an integral vertical post or offset, I, which is provided with a vertical recess or groove, K, in its rear side.

L represents a door which fits in the grooves G, and is adapted to close the rear side of the shell or body A. The said door is wedge-shaped in vertical transverse section, and is thereby adapted to the shape of the grooves 45 G, so that when the door is closed down into

the said grooves it becomes firmly wedged therein. The lower corners of the door are rounded, as at M, and the free end of the door is slightly curved. The opposite side of the door is provided near its upper corner with a 55 projecting shoulder or offset, N, which extends through a vertical slot, O, which communicates with the upper end of one of the grooves G. The extreme upper corners of the door L are provided with outwardly-projecting ears P, 60 which engage the rear upper edges of the sides of the shell or body when the door L is closed. R represents a hinge-bolt which extends transversely through the offset or shoulder N at a point a slight distance above the center of the 65 door and through aligned openings in the opposing flange E and posts or offsets H. The body of the shell or iron is provided on its upper side with transverse ridges or tongues S.

T represents the heating-core, which is made 70 of iron or other suitable heat-conducting material, and is provided on its lower side with transverse grooves U, adapted to engage the tongues S when the core is placed in the shell or body of the iron, and thereby prevent the 75 core from moving longitudinally therein. In the rear end of the core is an opening, V, adapted for the insertion of the usual stove hook or lifter, whereby the core may be handled when hot.

W represents an inner shell, which is made 80 of a single piece of sheet-iron and comprises the top X and the depending sides Y, which converge at their front ends, one of the said sides being lapped over the other and secured 85 thereto by means of rivets Z. The rear end of the inner shell is open. The said shell is adapted to fit between the shoulders or posts in the outer shell, and thereby to be secured in the latter at a distance from the sides thereof, 90 and thus form a space or chamber, A', between the inner and the outer shells, in which a filling of plaster-of-paris or other non-conductor of heat is placed.

B' represents a top or cap plate adapted to 95 fit on the upper edges of the shell or body A, and provided at its corners with vertical openings, through which screws C' are passed and caused to engage threaded openings in the upper ends of the posts or offsets H and I. The 100

cap or cover is thus firmly secured to the top of the shell or body, and is adapted to be removed therefrom at pleasure.

It will be observed by reference to Fig. 1 that the space is left between the upper side of the inner shell and the cap or cover of the body or shell A for a non-conducting filling. C² represents a handle having depending arms D', the lower ends of which are screwed in openings made in the top plate, B'.

We are aware that it is not broadly new to provide the shells or bodies of polishing and smoothing irons with vertically - movable hinged doors, and this therefore we disclaim.

15 The groove G and the door are made wedge shape in order to cause the door to fit snugly in the groove when closed, and thereby prevent ashes and dirt which may become detached from the core from working their way out of the shell and smutting the goods when the iron is in use. The wedge shape of the groove and door also enables the door to be more readily opened, as it prevents binding in the upward movement.

25 The posts cast on the inside of the iron serve several functions. They form one side of the groove G, hold the inside shell to its place, and also afford a place for the screws which hold the top.

30 Having thus described our invention, we claim—

1. In a core-heating iron, the combination of the shell or body A, having the vertical wedge-

shaped grooves G in opposing sides at its rear end, and the door L, adapted to close into the 35 said wedge-shaped grooves, the said door being wedge-shaped in vertical transverse section, and having one side secured in one of the grooves G by a hinge-bolt, substantially as described. 40

2. In a sad-iron, the outer cast-iron shell, H, having the posts or shoulders formed integrally therewith on its inner side, combined with the inner sheet-iron shell in a single piece and fitting against the shoulders or posts, so as 45 to be held by the shoulders or posts at a distance from the outer shell and form a space between the inner and outer shells, as set forth.

3. In a sad-iron, the combination of the shell H, having the posts or shoulders formed integral on its inner side, said posts or shoulders forming one side of the groove G, and also serving as a means of attachment of both the top plate and inner shell, the door L, hinged in the groove G, the inner wrought-iron shell fitting 50 against the posts or shoulders, and the top plate secured to the posts or shoulders, as set forth.

In testimony that we claim the foregoing as our own we have hereto affixed our signatures 55 in presence of two witnesses.

ISAAC C. H. GILMORE.
HENRY B. STAFFORD.
